UNITED STATES PATENT OFFICE.

BENJAMIN NEWMAN, OF NEW YORK, N. Y.

SMOKE-HELMET.

1,177,438.

Specification of Letters Patent. Patented Mar. 28, 1916.

Application filed April 29, 1913. Serial No. 764,461.

To all whom it may concern:

Be it known that I, BENJAMIN NEWMAN, a citizen of the United States, residing at New York, in the county of New York and State of New York, have invented certain new and useful Improvements in Smoke-Helmets; and I do hereby declare the following to be a full, clear, and exact description of the invention, such as will enable others skilled in the art to which it appertains to make and use the same.

This invention relates to new and useful improvements in smoke helmets or respirators for firemen, mechanics, laborers, and all persons whose work is of such a nature that they are constantly exposed to smoke, dust or deleterious gases.

The principal object of this invention contemplates the provision of a smoke helmet which may be readily positioned over the face of the wearer and which carries means for preventing all smoke and gas from entering the helmet.

A further object of this invention is to construct the helmet in such manner that by merely placing it on the wearer's face, the various parts of the device will act to effect a hermetic sealing of the edges of the helmet against the adjacent portion of the wearer's face and head.

The above and additional objects are accomplished by such means as are illustrated in the accompanying drawings, described in the following specification and then more particularly pointed out in the claim which is appended hereto and forms a part of this application.

With reference to the drawings, wherein I have illustrated the preferred embodiment of my invention as it is reduced to practice, and throughout the several views of which similar reference numerals designate corresponding parts: Figure 1 is a front elevation of the helmet. Fig. 2 is a section on the line 2—2 of Fig. 1. Fig. 3 is a rear elevation of the helmet disclosing the arrangement of the interior members; and Fig. 4 is a section on the line 4—4 of Fig. 2, illustrating in detail the sealing flap carried by the face of the helmet.

Proceeding now to the description of the drawings, the helmet includes a face ring 1 formed of wire or other similar and suitable material and shaped to approximately conform to the contour of the human face. Carried on the front edge of the ring 1 and

approximately mid-way the length thereof are the spaced semi-circular ribs 2 and 3, held in rigid fixed relation to each other by vertical stays 4, 5 and 6. The members 3, 4, 5 and 6 are preferably wrapped with a cloth or fabric of any suitable nature for the obvious purpose of protecting the wearer's face. Connected at their upper terminals to the stay 5 and at their lower terminals to the lower portions of the sides of the ring 1, are a pair of arcuate stays 7 and 8. A similar set of arcuate stays 9, 10 and 11, respectively connect the members 4, 5 and 6 to a central point at the upper curved portion of the ring 1, as at 12. An eyelet 13 is formed integral with the members 9 and 11 to form a convenient means for hanging the helmet on the wall within easy reach of the user of the device. A substantially semi-circular stay 14 is carried by the lower cross member 15 of the ring 1, and extends forwardly therefrom, being of smaller size than the members 2 and 3. Connecting the member 5 with the terminals of the cross bar 15 are a pair of arcuate stays 16 and 17 which may be wrapped to the members 14 at the inner terminals thereof by a suitable cloth or fabric strip 18.

The entire structure above disclosed, including the face ring and the stays, is covered with any suitable cloth material indicated by the letter A. This cloth is provided with an opening corresponding in size with the stays indicated by the numerals 2, 3, 4 and 6. Mounted between the stays and the cloth covering is an isinglass strip 19 provided for the obvious purpose of allowing the wearer of the helmet to see through it and still be protected from the smoke and gaseous fumes.

An air tube 20 is attached to the lower portion of the cover A, being secured in a reinforcing strip of leather, paste board or other suitable material arranged between the two members 16 and 17. The tube 20 may be removably attached to a fixed sleeve 21, the inner terminal of which is provided with a funnel 22 for the obvious purpose of dispersing the incoming air. The tube 20 is of sufficient length to reach the floor when the helmet is in assembled position on the wearer's face, and is provided at its lower terminal with a funnel mouth 22'. In this connection it is to be observed that if the helmet is employed by a householder who is confined in a burning house, that he

may pass the tube out of the window, thus getting an adequate amount of fresh air to prevent his suffocating by the inhalation of smoke, and that the wearer may, at the same time, employ the tube 20 and funnel 22' as a megaphone in his cries for help. It is also to be observed that since the tube is of sufficient length to reach the floor or surface on which the wearer of the helmet is standing, that a supply of comparatively fresh air will be thus assured to the user of this device, for it is a well known fact that even in burning buildings filled with smoke, a fresh current of air will be found for a small space above the floors of each room.

As a means for assuring a sealing of the face ring on the cheeks and other portions of the wearer's face and head, there is provided a flexible flange 23 formed of rubber, fabric, or any other suitable material which will not have a tendency to chafe or inconvenience the wearer. As illustrated in Fig. 4, this flange is fixed to the ring and extends inwardly, being directed at an angle to the plane of the ring.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction,

proportion and arrangement of parts may be resorted to, when required, without sacrificing any of the advantages of my invention, as defined in the appended claim.

What is claimed is:

In a smoke helmet structure, a face covering constructed of non-porous fabric, longitudinally and laterally disposed braces for shaping said fabric for conformation to the configuration of the wearer's face, the uppermost parts of said laterally disposed braces being spaced for extending across the brow of the wearer, the lateral brace positioned below the upper lateral brace of said pair positioned below the eyes of the wearer, said fabric covering intermediate said lateral braces being provided with a transparent window, the lateral and longitudinal braces which engage the wearer's face being wrapped with non-irritating material, a sleeve mounted in the lower end of said fabric covering, a funnel shaped sleeve attached to said first named sleeve and flaring upon entrance into the face covering, a flexible air conduit communicationally connected to said first named sleeve for facilitating the passage of air into the face covering.

In testimony whereof I affix my signature in presence of two witnesses.

BENJAMIN NEWMAN.
